DESIGN FOR A FLEXIBLE POCKET RECEPTACLE

Warner R. Buxton, Longmeadow, Mass.

Application May 29, 1940, Serial No. 92,676

Term of patent 14 years

To all whom it may concern:

Be it known that I, Warner R. Buxton, a citizen of the United States, residing at Longmeadow, in the county of Hampden and State of Massachusetts, have invented a new, original, and ornamental Design for a Flexible Pocket Receptacle, of which the following is a specification, reference being had to the accompanying drawing, forming part thereof.

Fig. 1 is a top plan view of a flexible receptacle showing my new design; and

Fig. 2 is a front elevational view thereof.

The design is confined to the front of the receptacle, the back being substantially plain.

The dominant features of the design reside in the portions shown in full lines.

I claim:

The ornamental design for a flexible pocket receptacle, substantially as shown and described.

WARNER R. BUXTON.
